UNITED STATES PATENT OFFICE.

HIRAM WALKER, OF ILE AUX PÊCHES, CANADA.

VAPORIZER.

SPECIFICATION forming part of Letters Patent No. 581,837, dated May 4, 1897.

Application filed February 8, 1897. Serial No. 622,555. (No model.)

To all whom it may concern:

Be it known that I, HIRAM WALKER, a citizen of the United States, residing at Ile aux Pêches, in the county of Essex, Province of 5 Ontario, Canada, have invented a new and useful Improvement in Medicators, of which the following is a specification.

The nature of my invention relates to an improved form of receptacle or case for containing a medicament whose therapeutic virtues may slowly vaporize and be inhaled by the wearer of the device to his benefit in diseases of the respiratory organs or that can be reached through them. 10
The invention consists in the novel and peculiar construction of the device, as more fully hereinafter set forth.

Figure 1 is a front elevation of the case. Fig. 2 is an elevation of the opposite side. 20 Fig. 3 is a cross-section at X X. Fig. 4 is a similar section showing the two halves of the case separated.

Like letters refer to like parts in the several figures. 25
In the drawings, A represents the body of the case, preferably circular in form, with a flange at the periphery. A tongue a projects from it and encircles a pendant b, by means of which it may be suspended from the wearer's neck by a cord passing around it. The 30 central portion is sunk so that a small drop-handle c may lie flush therein and not abrade the skin.

A' is a flanged cap or cover fitting snugly 35 over the flange of the body A and is notched at the proper point for the reception of the tongue a on the latter. It is sunk inwardly

nearly to the periphery, so as to receive a disk A², lying flush therein and centrally pivoted thereto by a rivet d. Several concentric 40 rows of coincident pin-holes e are drilled through the cover and disk. To bring the two sets of holes in opposition, a projection f, forming part of the disk A², is used as a handle and springs into a notch g, cut in the edge 45 of the flange of the case to hold it in place. The medicament inclosed in the case may now slowly vaporize under the heat of the wearer's body, the escaping fumes being inhaled by the invalid. By moving the disk a little 50 and springing the lever f into another notch in the cover the holes in the cover are closed by the disk and the emission of the vapors arrested.

This medicating device, being small and 55 compact, may be worn continuously, but most sufferers from respiratory disorders will find its use at night sufficient and efficacious.

The flush handle c is for convenience in fitting the two parts of the case together. 60

What I claim as my invention, and desire to secure by Letters Patent, is—

The herein-described medicament-vaporizing device, consisting of the flanged body A; the flanged and perforated cover A' fitting 65 over it; the perforated disk A² pivoted thereto, and provided with the lever f engaging with the notch g in the flange of said cover, substantially as and for the purpose set forth.

HIRAM WALKER.
